US0D1107496S

(12) **United States Design Patent** (10) Patent No.: **US D1,107,496 S**
(45) Date of Patent: ** Dec. 30, 2025

(54) **FOOD PROCESSOR CONTAINER**

(71) Applicant: **Capbran Holdings, LLC**, Los Angeles, CA (US)

(72) Inventor: **Robert Finance**, Hartford, CT (US)

(73) Assignee: **Capbran Holdings, LLC**, Los Angeles, CA (US)

(**) Term: **15 Years**

(21) Appl. No.: **30/001,448**

(22) Filed: **Apr. 28, 2025**

CLAIM

The ornamental design of a food processor container as shown and described.

DESCRIPTION

FIG. 1 is a perspective view of a food processor container, showing my new design;

FIG. 2 is a first side elevation view thereof;

FIG. 3 is a second side elevation view thereof;

FIG. 4 is a third side elevation view thereof;

FIG. 5 is a fourth side elevation view thereof;

FIG. 6 is a top plan view thereof; and,

FIG. 7 is a bottom top view thereof.

(Continued)

The broken lines in the figures are included for the purpose of illustrating portions of the food processor container, and form no part of the claimed design.
